UNITED STATES PATENT OFFICE.

ALICE J. WINSLOW, OF KALAMAZOO, MICHIGAN.

THREAD HOLDER AND CUTTER.

SPECIFICATION forming part of Letters Patent No. 244,103, dated July 12, 1881.

Application filed March 8, 1881. (No model.)

To all whom it may concern:

Be it known that I, Mrs. ALICE J. WINSLOW, a citizen of the United States, residing at Kalamazoo, county of Kalamazoo, State of Michigan, have invented a new and useful Thread Holder and Cutter, of which the following is a specification.

My invention has for its object to construct such devices entirely of a single piece of wire 10 in such a manner that greater convenience and cheapness are effected, and the devices are made more available for connecting with the spools in their manufacture and shipped with them to the trade, and at the same time adapted for detaching from one spool and connecting with another quickly and practically.

The construction of my device consists in bending a piece of wire in the form of a hair-pin, the portion bent back upon itself being 20 designed for detachable connection with the hole in a spool, and in forming the free ends terminating on top of the spool in a cutter or retainer, or both; or the portion inserted in the spool may be formed spirally, by which latter 25 construction I design to effect an equivalent of the former, as no material change is wrought.

In the accompanying drawings, forming a part of this specification, Figure 1 shows the device formed with a cutter and retainer attached to a spool. Fig. 2 is a perspective of 30 said device detached from the spool; Fig. 3, a sectional view of a spool, showing the connecting pendant of the device formed spirally.

F shows the device having blade c and 35 thread-retaining hook a on either end respectively of the wire terminating with the hair-pin portion. The rise in the wire between the blade and hook serves to rest the thumb on

when revolving the spool in unwinding the thread. This projection v may be much lower, 40 if desired, or dispensed with entirely.

d in Fig. 3 shows the spirally-formed connecting portion. In this construction only the blade a is shown, but the retainer c can be readily formed on this device by doubling the 45 wire before forming the spiral portion.

In operating the device when it contains only the blade c, the thread t may be held by the fingers of one hand and thrown over the blade with the other. When the device contains both the cutter c and thread retainer or holder a the thread may be first caught in the retainer and then be thrown over the blade and severed in the usual manner of said devices. 55

What I claim as new, and desire to secure, is—

1. In combination with a spool, the thread holder and cutter consisting of the hair-pin-shaped shank provided with the thread cutter 60 and retainer, substantially as shown and described.

2. In a thread holder and cutter, the hair-pin-shaped shank or equivalent shown, provided with the cutter and retainer, substantially as described and shown. 65

3. In combination with a thread-spool having the hole through the center, the holder and cutter consisting of the hair-pin-shaped shank F, the cutter c and retainer a, substantially as 70 described and shown.

ALICE. J. WINSLOW.
